UNITED STATES PATENT OFFICE.

MIKE POLIK, OF TRIADELPHIA, WEST VIRGINIA.

POWDER CAN.

Application filed August 29, 1924. Serial No 734,955.

To all whom it may concern:

Be it known that I, MIKE POLIK, a citizen of Hungary, residing at Triadelphia, in the county of Ohio and State of West Virginia, have invented certain new and useful Improvements in Powder Cans, of which the following is a specification.

This invention relates to new and useful improvements in powder cans.

The primary object of the invention is to provide a powder can suitable for use by miners for carrying blasting powder and squibs or fuses.

A further object of the invention is to provide a powder can with a removable insulating covering or casing which will reduce the liability of an accidental explosion of the contents of the can to a minimum.

A still further object of the invention is the provision of an insulating casing or covering which may be removably fitted to a powder can in such a manner that all danger of the contacting of an electrically charged element with any part of the can is eliminated.

Other objects and advantages of the invention will be apparent during the course of the following description.

In the accompanying drawing forming a part of this specification and in which like numerals are employed to designate like parts throughout the same—

Figure 1 illustrates a side elevational view of the powder can embodying this invention with the covering or casing properly fitted thereto,

Figure 2 is an edge elevational view of the structure illustrated in Fig. 1,

Figure 3 is a fragmentary side elevational view of the lower portion of the can with the flap portions of the casing or covering partially disconnected for illustrating the manner in which the casing or covering may be removed from the can,

Figure 4 is an elevational view of the structure illustrated in Figs. 1, 2 and 3 and shows the means employed for maintaining one of the casing closure flaps in its closed position,

Figure 5 illustrates a sectional view of the can and casing taken upon lines V—V of Fig. 1,

Figure 6 illustrates a bottom plan view of the structure illustrated in the aforementioned figures, and

Figure 7 illustrates a detail top plan view

of one of the removable plugs employed for closing the filler and discharge openings of the can.

In the drawings, wherein for the purpose of illustration is shown a preferred embodiment of this invention, the numeral 5 designates the powder can which may be manufactured from any suitable metallic material and is preferably of flask formation. This can 5 has a tapered neck 6 which terminates in an opening 7 at its upper end. Inserted through one side of the tapered neck 6 and projecting inwardly and outwardly of the wall of the can 5 is a tubular receptacle 8 which is closed at its inner end and opened at its outer end and is employed for receiving squibs or fuses used by a miner for firing his powder charges.

The body portion 9 of the casing or covering is formed from a single blank properly cut to fit the sides of the body portion of the can 5, the tapered neck 6, and the projecting portion of the supplemental receptacle 8 and to be maintained in the proper shape to fit such parts of the can by stitching the adjacent edges of the blank at 10, 11 and 12 to form the seams illustrated at these various points. In Fig. 5 the opening 7 is illustrated as having the casing or covering terminating in alignment therewith and entirely encircling the metallic portion of the can which forms the said opening. It is to be understood that the portion of the insulating blank which encloses the projecting part of the auxiliary receptacle 8 also terminates at the edge of its upper open end.

The oval-shaped bottom portion 13 of the casing or covering is stitched in the direction of its length and for approximately half of its periphery, as at 14, to the bottom edge of the body portion of the casing, as illustrated. The remaining portion of the periphery of the bottom 13 has stitched thereto a substantially rectangularly-shaped flap 15 which is intended to be positioned to extend transversely around the bottom portion of the body of the blank, as illustrated in Fig. 3 and to be attached to said body portion, at its free longitudinal edge, by the snap fasteners 16. It will now be seen that the entire can is enclosed in the casing or covering. For the purpose of preventing moisture or any foreign substance from working in between the metallic can and the casing or covering, preferably around the

flap 15, a second flap 17 is stitched to the body portion of the casing along its inner longitudinal edge, as at 18, and is also stitched for a portion of its transverse edges, 5 as at 19, to the body portion of the casing or covering. This additional flap 17 may now be positioned for overlying all of the edges of the first mentioned flap 15 and is held in its overlying or sealing position by 10 means of the snap fasteners 20 which are associated with the unstitched portions of the transverse edges of this flap 17.

For the purpose of closing the openings to the interior of the body portion 5 of the 15 can and the auxiliary receptacle 8, plugs 21 are provided and encased in the same insulating material which forms the covering or casing, as at 22, see Fig. 5. Suitably secured to the outer end face of each encased 20 plug 20 is a flaring cap 23 which is formed of the same insulating material and is adapted for encircling the edge of the blank forming the casing or covering which is arranged in proximity to the said openings. 25 It will be seen that this cap 23 forms a backing or covering for preventing leakage around the plug 21. It is also to be understood that the open end of the auxiliary receptacle 8 is closed by a similar plug and cap. For the purpose of aiding in removing these plugs and caps and for preventing the same from being lost, cords 24 and 25 are inserted through the plugs, as at 26, see Fig. 30 5, and knotted at their inner ends, as at 27. 35 The free ends of these cords 24 and 25 are secured to the body portion of the casing or covering by the straps 28 and 29 respectively which are stitched to the said casing or covering.

40 For the purpose of permitting the can to be carried from place to place by a miner, a plurality of straps 30 are stitched at their opposite ends to the body portion of the casing or covering and are adapted for receiving the strap 31 which is laced therethru and is intended to have its ends 31^a connected to a shoulder strap or handle strap by means of suitable buckles. This shoulder strap or handle strap with its buckles has 45 not been illustrated as it does not form a part of the present invention.

50 It will be seen that when the user of this can intends to pour powder therefrom, the plug 21 is removed from the opening 7, by 55 pulling upon the cord 24. The powder may then be poured from the can. When the owner of the can desires to obtain a squib or fuse, the remaining cap or the cap closing the auxiliary receptacle 8 may then be 60 removed by pulling upon the cord 25.

These straps and plugs may as readily be returned to their proper places. Should the metallic powder can become unsuitable for use, the outer sealing flap 17 may be disconnected at the snap fasteners 20, from the 65 body portion of the casing or covering and folded upwardly, as illustrated in Fig. 3. The snap fasteners 16, for the inner flap 15, may then be separated and this flap 15 pulled downwardly, as illustrated in Fig. 3, 70 for removing the bottom 13 of the casing from the bottom end of the can. The can may then be withdrawn from the casing and a new can put in its place.

It is to be understood that the form of 75 this invention herewith shown and described is to be taken as a preferred example of the same, and that various changes in the shape, size, and arrangement of parts may be resorted to without departing from the spirit 80 of the invention or the scope of the subjoined claims.

Having thus described the invention, I claim:—

1. In a device of the type described, the 85 combination with a metallic powder can having the form of a flask, of an insulating removable covering for entirely enclosing said can, said covering including a body portion, and a bottom having a portion of its edge permanently attached to said body portion, and having its remaining edge portion detachably attached to the body portion.

2. In a device of the type described, the 90 combination with a metallic powder can having the form of a flask, of an insulating removable covering for said can, said covering including a body portion, a bottom partially attached to said body portion, and a flap carried by the free portion of said bottom and adapted to be separably attached to one side wall of said body portion for maintaining the bottom in place.

3. In a device of the type described, the 95 combination with a metallic powder can having the form of a flask, of an insulating removable covering for said can, said covering including a body portion, a bottom partially attached to said body portion, a flap carried by the free portion of said bottom 100 and adapted to be separably attached to one side wall of said body portion for maintaining the bottom in place, and an auxiliary flap permanently secured to said body portion and detachably held in place to overlie 110 the free edges of the flap carried by the bottom.

In testimony whereof I affix my signature.

MIKE POLIK.
